Maurice Bloch
ATTORNEY

UNITED STATES PATENT OFFICE

WILLIAM KAHN, OF NEW YORK, N. Y.

FIRE EXTINGUISHER

Application filed December 21, 1928, Serial No. 327,511. Renewed March 25, 1931.

This invention relates to improvements in fire extinguishers and supporting means therefor, and has for one of its objects the provision of a fire extinguisher, having a glass seal, and a support therefor which will break or separate at a temperature of between 120° to 150° Fahrenheit, and means in line with the glass seal for breaking same when the support is so broken.

Another object of the invention is to provide normal supporting and seal breaking means for a fire extinguisher of the character referred to, said means comprising a bracket having a vertical slot therein, a pair of flexible metal ribbons on the said bracket soldered to each other with a solder fusible at a temperature of between 120° and 150° Fahrenheit to form a support for the extinguisher, and seal breaking means at the bottom of the said bracket in line with the seal.

Another object is to produce a device of the character described in which the maximum simplicity of construction and operation is secured.

Other objects and advantages will appear as the nature of the improvements is better understood, the invention consisting substantially in the novel arrangement and correlation of parts herein fully described and illustrated in the accompanying drawings, wherein similar reference characters are used to describe corresponding parts throughout the several views, and then finally pointed out and specifically defined and indicated in the appended claims.

The disclosure made the basis of exemplifying the present inventive concept suggests a practical embodiment thereof, but the invention is not to be restricted to the exact details of this disclosure, and the latter, therefore, is to be understood from an illustrative, rather than a restrictive standpoint.

The inventive idea involved is capable of receiving a variety of mechanical expressions, one of which, for the purpose of illustration, is shown in the accompanying drawings, in which;

Figure 1 is a side view partly in section of my improved fire extinguisher and support.

Fig. 2 is a fragmental perspective view of the extinguisher supporting means.

Fig. 3 is a fragmental rear elevation of the device and

Fig. 4 is a fragmental sectional view taken 55 on line 4—4 Fig. 3.

Referring now to the drawings in detail 5 indicates a tubular container which may contain any suitable fire extinguishing fluid 6 such as for instance carbon tetrachloride. 60 The said receptacle or container is provided with an internal annular shoulder 7 and a projecting annular lip or flange 8 against which shoulder and flange there is cemented or otherwise secured a sealing disk 9 preferably made of glass. An open cap 10 is screw threadedly secured to the reduced neck portion 11 of the receptacle and a rubber ring or washer 12 is placed between the glass disk 9 and inner surface of the cap 10 to make the 70 receptacle substantially water tight.

Secured to the receptacle 5 there is a substantially T shape slide member 14 the bottom corners 15 and 16 of which are bent outwardly the object of which will presently 75 be described. By means of the slide member 14 I am enabled to slidably mount the fire extinguishing receptacle on a bracket 17 provided with a T slot 18 to accommodate the said slide member 14. Secured to the bracket 80 17 to one side of the slot 18 there is a metal strip 19 provided with a bent up extension 20 to the underside of which there is soldered a flexible metal strip or ribbon 21 which is suitably secured to the bracket at the ad- 85 jacent side of the slot 18. This metal strip 21 is so formed as to provide a supporting bridge 22 upon which the bent up ends 15 and 16 of the slide member 14 are normally adapted to rest. The solder employed to connect the strips 19 and 21 at their juncture 90 23 has a fusing or melting point of between 120° and 150° Fahrenheit. The bracket 17 is provided at the bottom thereof with an extension 25 to which there is suitably secured 95 as by riveting a conical member 26 made of metal or other suitable material. The said member is in direct line with the centre of the glass closure or seal 9. The bracket 17 may be directly secured to a wall or by means 100

of an extension bracket 27 secured thereto it may be suspended from a ceiling.

As previously stated the receptacle containing the fire extinguishing fluid is normally supported on the bridge 21, and in case of fire when the temperature of the room has reached 120° or higher the solder at the joint 23 will melt and due to the weight of the receptacle it will slide down in the slot 18 in the bracket 17 and the glass closure 9 will be broken by the member 26 thus releasing the fire extinguishing fluid.

From the foregoing it will be seen that I have provided a simple and efficient fire extinguisher that is positive in action and one that does not depend upon any human agency to operate same.

Having described my invention what I claim as new and desire to secure by Letters Patent is:

1. In a device of the nature described, a receptacle adapted to contain fire extinguishing fluid, a breakable seal on one end of the receptacle, a bracket upon which the receptacle is slidably maintained, a melttable support to normally support the receptacle, and seal breaking means on the bracket outside the receptacle and in alinement with the seal to break same when the support is melted and the container drops down.

2. A fire extinguisher comprising a bracket, a receptacle adapted to contain fire extinguishing fluid, means for slidably mounting same on the bracket, a breakable seal at one end of the receptacle, a melttable support for normally supporting the receptacle, and seal breaking means comprising a pointed member outside the receptacle in alinement with the seal to break same when the support is melted and the receptacle drops down.

3. In a device of the nature described, a receptacle adapted to contain a fire extinguishing fluid, a breakable seal at one end of the said receptacle, a slide member on the receptacle, a bracket to slidably receive the said slide member, a support for normally supporting the receptacle thereon, comprising a pair of sections of flexible metal soldered together by a solder of a predetermined melting point, and means on the bracket for breaking the seal when the support is melted and the container slides down on the bracket.

4. A device of the nature described, comprising a bracket, a fusible support on the bracket adapted to be released at a predetermined degree of heat, a fire extinguishing fluid receptacle slidably mounted on the bracket and normally supported on the support and adapted to drop down by gravity when the support is released, a breakable seal at one end of the receptacle, and means outside of the receptacle in line with the seal for breaking same when the receptacle drops.

5. In a device of the nature described, a receptacle adapted to contain fire extinguish-

ing fluid, a breakable seal at one end of the receptacle, a slide member on the receptacle, a bracket to slidably receive the slide member, a fusible support on the bracket to normally support the slide member and receptacle, and means on the bracket for breaking the seal when the support is melted and the container slides down on the bracket.

WILLIAM KAHN.
